Inventor
William T. Dodd.

UNITED STATES PATENT OFFICE.

WILLIAM T. DODD, OF GATES, TENNESSEE.

PLOW.

SPECIFICATION forming part of Letters Patent No. 424,470, dated April 1, 1890.

Application filed August 23, 1889. Serial No. 321,768. (No model.)

To all whom it may concern:

Be it known that I, WILLIAM T. DODD, a citizen of the United States, residing at Gates, in the county of Lauderdale and State of Tennessee, have invented a new and useful Plow, of which the following is a specification.

My invention relates to improvements in plows; and it consists in certain novel features, hereinafter described and claimed.

In the accompanying drawings, Figure 1 is a perspective view of my improved plow. Fig. 2 is a rear elevation of the same. Fig. 3 is a detail sectional view. Fig. 4 is a horizontal section on the line through the plow-standard.

The plow-beam A is of the usual construction, and the standard B is formed integral with the beam and depends from the rear end of the same. The handles C are pivotally secured at their lower ends to the standard, and are held in a proper position by the braces D, which have their front ends pivoted to the beams and their rear ends adjustably secured to the handle. The handle can thus be raised or lowered, so as to suit the height of the driver. On the side of the beam at a point in advance of the braces I secure a band E, through which the colter F is inserted. The colter is provided at an intermediate point of its height with an offset or lateral shoulder G, so that it will be brought into the plane of the beam, and thereby made to run in the center of the furrow. The colter is held in the band by means of a wedge G', which is inserted downward through the band between one end of the same and the edge of the colter, so as to clamp the colter in the band. The colter is provided in its outer side with a vertical longitudinal series of notches or recesses H, which are engaged by the end of a set-screw I, mounted in the band, so that the colter can be adjusted to a greater or to a less depth and will be securely held at any point to which it may be adjusted. The colter is thus supported by the set-screw I, and when it is desired to adjust the angle of said colter a differently-shaped wedge G' can be substituted without removing the colter and de-

stroying the vertical height thereof which recent trials may have proven to be most desirable.

The blade or shovel J is secured to the front side of the standard at the lower end of the same and is given a rather sharp bend, so that it is caused to run under the surface of the ground, and thereby turn up the earth more thoroughly than if it were vertical and its point rested on or dug into the ground. 55 This peculiar formation of the shovel also reduces the draft of the plow, as the shovel can be more easily drawn through the earth.

To the rear side of the standard, at the lower end of the same, I secure the outwardly-projecting wing or covering-plate K, which extends to one side of the shovel and is adapted to throw the loose earth turned up by the shovel onto the plants. This covering-plate K is slightly twisted near the standard, 60 so that its front surface is inclined downward and rearward to more effectually throw the dirt onto the plants. This covering-plate is secured to the standard by a bolt inserted through the standard and the end of the 65 plate and a nut mounted on the end of the bolt and adapted to be turned up against the plate. By this arrangement the covering-plate will be securely held to the standard and at the same time may be adjusted so as 70 to deflect the dirt more or less directly onto the plants, as will be readily understood.

In practice the plow is drawn over the ground in the usual manner and will turn up the earth and throw the same over onto the 75 plants. As the plow is drawn along the colter will cut and divide the earth and the shovel follows directly behind the colter in the division thus made, so as to turn up the dirt and throw it rearward against the covering-plate, by which it will be deflected over onto the plants.

My device is very simple in its construction and arrangement of its parts, and will be found very efficient in cultivating corn and cotton. The colter can be readily adjusted to run to a greater or less depth, according to the nature of the ground, and the advantages of the device are thought to be obvious.

Having thus described my invention, what I 100

claim, and desire to secure by Letters Patent, is—

The combination of the standard having a longitudinal slot in its lower end, the shovel 5 secured to the front side of the standard, the covering-plate having its front side inclined downward and rearward and its end bearing against the rear side of the standard, and the securing-bolt inserted through the end of the

plate and the slot in the standard, as set forth.

In testimony that I claim the foregoing as my own I have hereto affixed my signature in presence of two witnesses.

WILLIAM T. DODD.
